UNITED STATES PATENT OFFICE.

PARKER FARNSWORTH MOREY, OF PORTLAND, OREGON.

WATER OR OTHER ENGINE.

SPECIFICATION forming part of Letters Patent No. 355,097, dated December 28, 1886.

Application filed September 20, 1886. Serial No. 213,032. (No model.)

To all whom it may concern:

Be it known that I, PARKER FARNSWORTH MOREY, of Portland, in the county of Multnomah and State of Oregon, have invented new 5 and useful Improvements in Water and other Engines, of which the following is a full, clear, and exact description.

This invention, although not restricted to the use of any one propelling agent, is more particularly intended to be applied to engines propelled by water under pressure, and will here be described accordingly.

In a water-engine it is important that the water should be admitted without restriction 15 and be discharged without resistance. This result cannot be obtained by the use of the ordinary slide-valve or other valves in general use, which open and close gradually by the direct application of mechanical force, and if 20 such mechanical action as derived from the engine be quickened it is done at the expense of much power, thereby detracting from the capability of the engine. To obviate this and to obtain a quick and positive action, I use a 25 system of automatically-operating differential valves controlled by the action of a mechanically-actuated auxiliary valve, which takes but little power to work it, while the differential valves provide for admitting the water with 30 out restriction and for discharging it without resistance—that is, comparatively speaking—and in connection with this system of valves I make the piston of the engine, which is a reciprocating one, also a differential one, and 35 combine with it a general receiving-chamber, whereby all valves for directly controlling the supply and discharge of water to and from the smaller end of the piston are dispensed with, all substantially as hereinafter shown and de- 40 scribed.

Reference is to be had to the accompanying drawings, forming a part of this specification, in which similar letters of reference indicate corresponding parts in all the figures.

45 Figure 1 represents a partly-sectional plan of a water or other like engine embodying my invention; Fig. 2, a partly-sectional longitudinal elevation of the same upon the line *x-x* in Fig. 1, and Fig. 3 a vertical transverse section 50 upon the line *y-y* in Fig. 1.

A A' indicate the cylinder of the engine, which is a reciprocating-piston one, and, as

here shown, occupies a horizontal position, and B is a main or general water-receiver, upon or over which said cylinder is mounted. Water 55 under pressure, as from a main or other source, is freely introduced at *b* to said receiver B, and also by any suitable connections—as, for instance, at *w*, Fig. 3—to an auxiliary valve-chest, C. The portion A' of the cylinder of 60 the engine is of double the area, or thereabout, as the portion A.

D D' is the reciprocating piston of elongated construction, and which may be of tubular form, with an intermediate partition or block, 65 *z*, to separate its larger head or end, D', from its smaller head or end, D, said heads or ends being suitably packed, as at *c c*, to work as a differential piston within the enlarged and reduced portions A A' of the cylinder. 70

Arranged through the partition *z*, transversely of the engine-cylinder and through slots *d d* in the sides of the cylinder, is a shaft or cross-head pin, *e*, carrying on its ends pitmen or connecting-rods *f f*, by which rotary 75 motion is communicated from the reciprocating piston by cranks *g g* to a main or engine-driving shaft, E.

The water-receiver B, which is represented as seated upon the base-frame F of the engine, 80 is in constant communication by a passage, *h*, with the smaller end, A, of the cylinder in front of the smaller end, D, of the piston, so that said end of the piston is always exposed to the full pressure of the water entering by the inlet *b*, 85 and it receives and returns the water to and from the front of it without the direct agency of valves. On the other hand, the water is admitted to and exhausted from the large end, A', of the cylinder back of the larger end, D', 90 of the piston by the action of an automatic differential inlet-valve, G, and an automatic differential exhaust-valve, H, by passages *i k* in or connecting with the larger end, A', of the cylinder. These differential valves are of 95 double-piston-like construction—that is, have an upper larger piston-head and a smaller lower piston-head—and work within valve boxes or chambers I J, their smaller heads controlling the passage of water to and from 100 the larger end, A', of the cylinder, and their larger ends or chambers, in which they work, being in communication by passages *l m* with the auxiliary valve-chest C.

The inlet differential valve G controls the passage *i* and an inlet-aperture in the water-receiver B, having a dip-tube, K, connected with it, whereby air collecting in the upper portion of the water receiver or reservoir B is prevented from escaping. The exhaust differential valve H controls the escape of the water passing from the larger end of the cylinder through the passage *k*, cavity *o*, and aperture *n* into and discharged by the outlet *r*.

L is the auxiliary valve arranged within the chest C, and which may be a common D-slide one. This valve controls the passages *l* *m*, which lead to the top of the valve-chests I J, and an intermediate exhaust-passage, *s*. It is actuated by the engine through tappets *a* *a'* on its rod *b'* and an arm, *c'*, connected with the piston of the engine and passing out through a longitudinal slot, *d'*, in the engine-cylinder.

20 The engine may be reversed by simply changing the position of the valve-rod without any alteration of the tappets, and the speed of the engine may be regulated by the use of any ordinary governor—such as the "Pickering"—applied to the exhaust-pipe of the auxiliary valve. Various mechanisms, however, may be used for operating the auxiliary valve and different means for regulating the speed of the engine.

30 The operation is as follows: The connection between the main and the engine having been established at *b* in the water-receiver B and *w* in the auxiliary valve-chest C, the valve L is first set or shifted to exhaust through the passages *m* and *s* the water from over the larger end of the differential exhaust-valve H. This relieves pressure from the larger end, *D'*, of the piston, and the water entering the receiver at *b* will act upon the smaller end, *D*, of the piston to force the latter back, the valve H rising or opening to freely discharge the water in rear of the piston through the nozzle or outlet *r*, while the valve G will be kept closed by the superior pressure on its larger end, as derived from the pressure in the valve-chest C, the passage *l* then being uncovered by the valve L. So soon, however, as the piston arrives at the end of its backstroke, the arm *c'* acts upon the back tappet *a'* to reverse the auxiliary valve L, which opens the passage *l* to the exhaust *s* and the passage *m* to the pressure of the water in the chest C. This causes the valve H to be closed and the valve G to open, which admits water under pressure from the receiver B to the back or larger end of the engine-piston, that, by the superior area of its end *D'*, is then driven forward against the pressure on the smaller end of the piston, forcing the water in the smaller end of the engine-cylinder back into the receiver and main, and to keep up the supply to the larger end of the cylinder. When the piston reaches the end of the forward stroke, the arm *c'* acts upon the forward tappet, *a'*, to again reverse the valve L, causing the valve G to close and the valve H to open, when the piston is driven backward, as be-

fore, by the pressure of the water on the smaller end of the piston, the larger end thereof being relieved of pressure, as hereinbefore described. This action is repeated indefinitely, 70 keeping up a continuous reciprocating motion of the piston, the driving pressure on the piston in both strokes being equal to that on the smaller end of the piston.

It will be seen that it is only the larger end 75 of the cylinder that is controlled by the valves to distribute the supply of water to and discharge of water from the engine. Both valves G and H, which should be packed to prevent escape of water to the under sides of their 80 larger heads, and may be provided with a suitable waste-outlet for any water thus passing them, as in the case of other differential valves, move simultaneously when opening and closing in reverse order, as described, and 85 their lift is made adjustable, to give the best results, by screw stop-pins *v* *v* in the covers of their chests I J.

By the use of the cross-head pin *e*, that passes through the piston, which is a trunk 90 one, the necessity for a piston-rod is dispensed with, and friction consequently reduced and room economized. This rod may either be of square or round shape in transverse section, and the walls of the slots *d* *d* in the cylinder 95 through which it works act as guides to it.

Any other fluid beside water and steam or other vapor or gas may be used for propelling the engine, if desired.

It will be understood that I make no claim 100 in this application to matter shown in the application having as its Serial No. 213,116, to the combination, with separate differential inlet and exhaust valves, of an auxiliary valve; to the combination, with one and the same 105 duct or branch which conveys the fluid to and from the ram, of a differential inlet-valve, a differential exhaust-valve, and an auxiliary valve, and to the combination of differential 110 inlet and exhaust valves, valve-cylinders of differential diameters, and an auxiliary valve.

Having thus described my invention, what I claim as new, and desire to secure by Letters Patent, is—

1. The combination of the differential engine-piston, the differential engine-cylinder, and automatic differential pressure - valves controlling the supply and discharge of the propelling agent to and from the engine, essentially as specified. 115

2. The combination of the water or fluid receiver or supply-chamber B, the differential cylinder A A', in free communication at its smaller end with said receiver, the differential inlet and outlet pressure - valves G H, 120 adapted to control the supply and exhaust at the larger end of the cylinder, the auxiliary valve-chest C, provided with a fluid-supply inlet, and the mechanically-operated auxiliary valve L, adapted to control the operation of 125 the differential valves, substantially as described. 130

3. The combination of the propelling fluid-receiver or supply-chamber B, the differential cylinder A A', in free communication at its smaller end with said receiver and having 5 longitudinal side slots, d d, and inlet and outlet passages i k at its larger end, the differential pressure-valves G H, controlling said passages i k, a valve controlling said differential valves, and the differential piston D D', pro-

vided with a cross-head pin or piece, e, arranged to project through the slots d d in the cylinder, substantially as and for the purposes herein set forth.
